ADJUSTABLE VENTILATOR SHIELD FOR
WINDOWS

Sampson D. Koch, Eldred, Pa.

Application December 16, 1946, Serial No. 716,577

1 Claim. (Cl. 98—99.3)

1

This invention relates to an adjustable ventilator shield for windows, and one of its objects is to provide a ventilator shield with a pair of guides in which the shield may be slidably adjusted, and to provide pivotally adjustable supports for the guides, so that the shield may be positioned in different planes of body adjustment, either inclined or vertical, and in spaced relation to the window sash.

Another object of the invention is to provide brackets for pivotally connecting the ventilator to the sides of a window frame, of simple construction, and which will safely hold the ventilator shield or deflector in any position of adjustment, within the range of effective adjustment.

With the above and other objects in view the invention comprises certain new and useful constructions, combinations and arrangements of parts, clearly described in the following specification, and fully illustrated in the drawings, in which:

Fig. 1 is a perspective view showing the device supported in a vertical position, with the sash partly raised.

Fig. 2 is a vertical sectional view, taken on line 2—2 of Fig. 1, looking in the direction of the arrows.

Fig. 3 is a similar view, showing the ventilator disposed in an inclined position.

Fig. 4 is a detail vertical sectional view, taken on line 4—4 of Fig. 2, looking in the direction of the arrows, showing a slightly wider deflector or shield.

Referring to the drawings, which illustrate the invention, 5 designates one side of a conventional window frame and 6 the companion side. On the side 5 a circular bracket plate 7 is secured by the screws 8 and 9, and to this bracket plate the bracket arm 10 is pivoted by the pin 11. To the frame side 6 the bracket arm 12 is pivotally secured by a bracket plate, similar to the plate 7, but not shown.

On the outer end of the bracket arm 10 a channel guide 13 is pivotally secured by the pin 14. On the outer end of the bracket arm 12 the channel guide 15 is pivotally secured by the pin 16. The two bracket arms 10 and 12 are supported by their base plates in a common horizontal plane, and are of equal length.

The channel guides are arranged in opposition to each other and also are of equal length, with the grooves 10a and 12b confronting each other. In the groove 12b the end of the plastic or glass shield pane or plate 17 is disposed, and in the groove 10a the end of the plastic or glass pane or plate 18 is disposed.

The inner end portions of the panes or plates

2

17 and 18 are arranged in overlapping relation to each other, and U-shaped guide hooks 19 and 20 are provided for holding these overlapping portions against each other for sliding adjustment.

Due to the fact that the channel guides 10 and 12 are entirely independent of each other, and the panes or plates 17 and 18 can be extended or contracted on each other, the unit 10 can be adapted to fit narrow or very wide windows.

Due to the tilting supports for the panes or plates 17 and 18, the deflector or extensionable shield, may be supported in a vertical position, as shown in Figs. 1 and 2, or in an inclined position as shown in Fig. 3.

Each of the pivotal connections is designed to offer a certain amount of friction, so that the adjustments made will not be accidentally changed.

It is understood that various changes in the details of construction, their combination and arrangement, may be made, within the scope of the invention, as defined by the claim hereof.

Having described the invention, I claim as new:

An adjustable window ventilator, comprising a bracket plate secured to each side of the window frame, a single bracket arm pivotally secured at one end to each of said bracket plates said bracket arm turning freely for about 180° relative to the window frame, a pair of grooved guides pivotally secured to the other end of said bracket arm intermediate the ends of said guide, a deflector member, the side ends of said deflector member being secured in the groove of each guide, said bracket arm permitting of turning of the guides with the deflector member for 360° relative to said bracket arm, thereby bringing about the possibility of positioning of the deflector member at any predetermined angle over a range of at least of 180°.

SAMPSON D. KOCH.
